(57) **CLAIM**

The ornamental design for a stanchion for C-pillar mounted vehicle rear wing, as shown and described.

DESCRIPTION

FIG. 1 is a front perspective view of a first embodiment of a stanchion for C-pillar mounted vehicle rear wing located in its environment;

FIG. 2 is a side perspective view thereof located in its environment;

FIG. 3 is a perspective view thereof;

FIG. 4 is a front view thereof;

FIG. 5 is a rear view thereof;

FIG. 6 is a bottom view thereof; and

FIG. 7 is a top view thereof;

FIG. 8 is a left side view thereof;

FIG. 9 is a right side view thereof;

FIG. 10 is a front perspective view of a second embodiment of a stanchion for C-pillar mounted vehicle rear wing located in its environment;

FIG. 11 is a side perspective view thereof located in its environment;

FIG. 12 is a perspective view thereof;

FIG. 13 is a front view thereof;

FIG. 14 is a rear view thereof;

FIG. 15 is a bottom view thereof; and

FIG. 16 is a top view thereof;

FIG. 17 is a left side view thereof;

FIG. 18 is a right side view thereof;

FIG. 19 is a front perspective view of a third embodiment of a stanchion for C-pillar mounted vehicle rear wing located in its environment;

FIG. 20 is a side perspective view thereof located in its environment;

FIG. 21 is a perspective view thereof;

FIG. 22 is a front view thereof;

FIG. 23 is a rear view thereof;

FIG. 24 is a bottom view thereof; and

(Continued)

FIG. 25 is a top view thereof;
FIG. 26 is a left side view thereof; and,
FIG. 27 is a right side view thereof.

The broken lines illustrate the environment in which the design is embodied and portions of the stanchion for C-pillar mounted vehicle rear wing which form no part of the claimed design.
